Inventor:
CARROLL BURTON,
Esq.
D. Anthony Lewis
his Attorney.

UNITED STATES PATENT OFFICE.

CARROLL BURTON, OF JOHNSTOWN, PENNSYLVANIA.

SPRING FASTENING FOR GUARD-RAIL CLAMPS.

Application filed October 19, 1923. Serial No. 669,569.

To all whom it may concern:

Be it known that I, CARROLL BURTON, a citizen of the United States, and resident of Johnstown, in the county of Cambria and State of Pennsylvania, have invented certain new and useful Improvements in Spring Fastenings for Guard-Rail Clamps, of which the following is a specification.

This invention relates to guard rail clamps used for the purpose of clamping a guard rail to the adjacent track rail, and more particularly to clamps of this class which are adjustable to different size rails and in which a wedge is used to draw the parts together.

One object of the present invention is to provide a clamp of the above class having means for locking the clamping wedge in position.

Another object is to provide a novel form of resilient pawl adapted to engage and automatically lock the clamping wedge in its various adjusted positions.

A further object is to provide a guard rail clamp having the novel construction, design and combination of parts hereinafter described in detail and illustrated in the accompanying drawings.

In the drawings, Figure 1 is an end elevation showing the clamp applied to a track rail and guard rail.

Figure 2 is a top plan of the same.

Figure 3 is a detail elevation of the clamping wedge showing the serrations.

Figure 4 is a plan of the spring or resilient pawl.

Referring more particularly to the drawings, the numeral 2 designates the clamping bar as a whole, which is provided with upturned or yoke shaped ends 3 and 4. The numerals 5 and 6 designate the track rail and guard rail, respectively, to which the clamp is applied.

The clamp bar 2 extends under the rails 5 and 6, and clamp chock 7 is positioned between the upturned end 3 of the bar 2 and the web of the guard rail 6. A pair of wedge shaped adjustable filler blocks 8 and 9, having their abutting faces serrated so as to lock with each other, are positioned between the rails 5 and 6 and a clamping wedge 10 is positioned between the end 4 of the clamp bar and the web of the track rail 5.

The chock 7, filler blocks 8 and 9, and wedge 10 may be made in various sizes for use with various sizes of rails and the same

clamp bar may be used with the various sizes of chocks, filler blocks and wedges.

The wedge 10 is provided with a straight rail engaging side 11 and an oblique clamp bar engaging side 12 adapted to engage the face of the upturned end 4 of the clamp bar 2. The oblique face or side 12 of the wedge 10 is provided with a flange 14 along its lower edge, which extends into an undercut recess 15 in the bar 2, and said flange is provided along its side face with a series of teeth or serrations 16.

A resilient pawl member composed of a piece of spring metal and comprising a flat body portion 17, and pawl ends 18 and 19 is mounted in the recess 15 so that the body portion 17 engages the rear wall of the recess and the pawl ends extend beyond the sides of the bar and resiliently engage the teeth or serrations 16 on the wedge 10.

The pawl ends 18 and 19 of the pawl member are formed by bending the spring metal piece back at substantially right angles to the body portion 17 and then reversely bending it back to form a spring loop and projecting the ends of the metal piece beyond the body 17 so as to form pawl points or tongues 20 and 21, respectively, extending into the path of the wedge 10 and adapted to automatically engage the teeth or serrations on the wedge. This novel pawl construction not only provides a novel automatically operating pawl, but provides a pawl structure which is self retaining on the clamp bar, is readily applied and removed, and provides a double engagement with the locking wedge.

In operation when the wedge 10 is inserted between the upturned end 4 of the clamp bar 2 and the web of the rail 5, it will be forced past the points 20 and 21 of the pawl ends 18 and 19 and the pawl points will automatically engage in the teeth or serrations 16, thus locking the wedge 10 against reverse movement.

While I have described and illustrated only one specific embodiment of my invention it will be readily understood that I do not wish to be limited to the specific embodiment described and illustrated, since the novel features to which this application is directed may be combined with various other forms of rail clamps and all of such combinations may be made without departing from the scope of my invention as defined in the appended claims.

I claim:—

1. A rail clamp comprising in combination, a clamp bar having one end formed to engage a clamp chock positioned between the end of the bar and a rail and having its other end formed to engage a clamping wedge, a wedge formed with a rail engaging side and an oblique clamp bar engaging side, and adapted to be positioned between a rail and the end of said clamp bar, said oblique side being provided with a series of serrations, and a double ended spring pawl mounted on said clamp bar and adapted to have both ends engaged in said serrations on said wedge to lock said wedge in position.
2. A rail clamp comprising in combination, a clamp bar having one end formed to engage a clamp chock positioned between the end of the bar and a rail, and having its other end formed to engage a clamping wedge, a wedge formed with a rail engaging side and an oblique clamp bar engaging side and adapted to be positioned between a rail and the end of said clamp bar, said oblique side being provided with a series of serrations, and a pawl mounted on said clamp bar and adapted to be engaged in said serrations to lock said wedge in position, said pawl being formed from resilient metal and having a flat portion engaging said clamp bar, and the ends of said pawl member being bent so as to tension against and engage in said serrations on said wedge.
3. In a rail clamp including a clamp bar and a wedge member having serrations along one edge, a resilient pawl for locking said wedge member in position, said pawl comprising a channel-shaped portion fitted over the end of said clamp bar, and said channel portion terminating at each end in a loop-like resilient pawl portion adapted to resiliently engage the serrations on said wedge.
4. In a rail clamp including a clamp bar and a wedge member having serrations along one edge, a resilient pawl for locking said wedge member in position, said pawl comprising a flat body portion extending along the end of said clamp bar, and loop-like pawl ends formed integral with said body portion and terminating in points or tongues adapted to automatically engage in the serrations on said wedge.
5. A rail clamp comprising in combination a clamp bar having one end formed to engage a clamp chock positioned between the end of the bar and a rail, and having its other end formed to engage a clamping wedge, a wedge adapted to be positioned between a rail and the end of the clamp bar, the side of said wedge adapted to be positioned next to the end of said clamp bar being provided with a plurality of serrations, and a resilient pawl mounted on said clamp bar and adapted to be engaged in said serrations to lock said wedge in position, said pawl being formed from resilient metal and having a flat portion engaging said clamp bar, and the ends of said pawl member being bent so as to form loop-like pawl ends terminating in points or tongues adapted to automatically engage in the serrations on said wedge.

In testimony whereof, I have hereunto set my hand.

CARROLL BURTON.
